UNITED STATES PATENT OFFICE.

ERNEST H. FREY, OF CLEVELAND, OHIO.

PRINTING CARD AND TYPE HOLDER.

1,149,570.

Specification of Letters Patent. Patented Aug. 10, 1915.

Application filed October 19, 1911. Serial No. 655,598.

To all whom it may concern:

Be it known that I, ERNEST H. FREY, a citizen of the United States, and resident of Cleveland, in the county of Cuyahoga and 5 State of Ohio, have invented certain new and useful Improvements in Printing Card and Type Holders, of which I hereby declare the following to be a full, clear, and exact description, such as will enable others 10 skilled in the art to which it appertains to make and use the same.

The objects of the invention are to provide a printing plate or card particularly adapted for use upon an improved form of 15 addressing machine and which is an improvement upon Letters Patent No. 871,581 issued November 19, 1907, to me for a printing card.

One feature of the invention is a printing 20 plate or type holder provided with an indexing means upon its rear surface, which may be an index card secured thereto, or a printed or otherwise affixed or stamped index thereon, which preferably includes the full 25 name and address so that the plate can readily be identified by a glance. In this manner the size of the plate may be greatly reduced below the size of the plate in ordinary use, since in index plates heretofore 30 known the upper surface has been extensive enough to provide a space for the printing plate and also for the index card or printed index of any character.

Further objects of the invention are to 35 provide an attachable and detachable indexing card for the general classification of the indexes, and further to provide means for detachably securing an index card to the rear face of the printing plate or type 40 holder.

A further feature of the invention is to provide the printing plate or type holder with an opening or openings through which if desired the reading matter on the index 45 card can be plainly read from the upper surface of the holder, without turning the plate over, and an important additional feature is the utilization of the upwardly turned edges of some of these openings to 50 form dove tailed guides and securing means for the printing plate or type, which by this means can be inserted at pleasure in any order desired between these openings. In this manner the address and type or linotype 55 will be closely adjacent to corresponding

lines of the address or other printed matter, and thus space is greatly economized.

The invention further comprises means for attaching the type or type plate holder to the table of an addressing machine, and 60 also consists in the combination and arrangement of parts and construction of details as hereinafter described, shown in the accompanying drawings and specifically 65 pointed out in the claims.

In the accompanying drawings Figure 1 is a plan view of the upper face of a printing plate or type holder provided with longitudinal sight openings through which the address can be read. Also the edges of these 70 openings are utilized as means for securing the type or line or type printing plate in line; Fig. 2 is a side elevation of several of the devices piled upon each other; Fig. 3 is a bottom view of a modified form of index 75 showing the name and address card placed upon the lower side of the type holder; Fig. 4 is a transverse section thereof; Fig. 5 is a plan view of a modified form of type holder showing a large opening through which 80 other matter than the address can be read if so desired; Fig. 6 is a plan view of one of the spring keepers.

In these views 1 is the type holding plate 85 which is preferably provided with backwardly turned lugs 2, 2, in which an index card 3 can be secured to the back of the plate and also with longitudinal slots 4, 4. The index card 3 can be provided with the 90 name and address in printed or written characters arranged in lines which can be read through the above mentioned slots.

In Figs. 1 and 4 the plate is shown provided with longitudinal slots 4, 4. Through 95 these slots the name and address can be read on the card below without turning the card over. This is a very convenient form for general use since the card can be read clearly when in place in the addressing machine. The edges of the slots 4, 4, are turned upward as at 4', 4' and inclined so as to form dove tailed grooves in which the type or printing or linotype plates 6, 6, can be inserted and the lines of type will be intermediate of the open slots 4, 4, and will run parallel therewith, the lines 5, 5, of the name and address will show through the 100 slots.

The bent springs S, S are detachably 110 snapped into place at the ends of the line

of type and prevent them from moving. At one end of the card small upwardly turned integral lugs L, L, can be used as stops in place of the springs.

5 In Fig. 5 a larger opening is shown exterior to the printing space which may be used with a wider card and permits of the use of more descriptive printed matter. This larger opening can be used with or 10 without the slots 4, 4, and as many openings can be made as desired. At the ends of the plate 1 are shown flanges downwardly and inwardly turned at 9.

When piled in the manner shown in Figs. 15 2 and 4 the pasteboard card will be on the bottom and will present a soft surface to the printing type or plate below, or the edges 9 may be high enough to prevent contact. The type holders may be provided 20 with detachable type or the type characters may be raised thereon by means of dies or cemented thereon. A general index tag 7 may be provided with tongues 8, 8, which are integral with the card and project beyond the edge of the plate. And I believe 25 myself also to be the first to conceive of a card index holder having slotted sight openings, the upwardly turned edges of which are utilized to hold type.

30 Having described the invention what I claim as new and desire to secure by Letters Patent is:

1. The combination with a type holder, of an index card secured to the underside of

said type holder, said type holder provided 35 with longitudinal slots the edges of which are turned upward to provide receiving flanges for type upon the upper side of said plate, the reading matter on said card being legible through said slots between said type 40 holders and beneath the same.

2. The combination with a type holder provided with parallel slots the edges of which are turned upwardly to provide holding flanges forming dove tailed spaces between which the type may be secured, said type spaces alternating with said slots, of an index card secured underneath said type holder, the index matter being legible through said slots. 45

3. In combination with a type holding plate, said plate provided with a series of parallel slots, the edges of which are formed from material taken from said slots and which are turned upwardly to form dove tail type securing means, and also provided with an opening exterior to said type securing means, and an index card attached to the underside of said plate, the reading matter on said card being legible through said 55 slots and opening.

In testimony whereof, I hereunto set my hand this 28th day of September 1911.

ERNEST H. FREY.

In presence of—
L. R. CANFIELD,
Wm. M. MONROE.
